UNITED STATES PATENT OFFICE.

WILLIAM F. LAUTENSCHLAGER, OF CINCINNATI, OHIO, ASSIGNOR TO LORENZ MUTHER,
OF BOSTON, MASSACHUSETTS.

CEMENT-APPLYING MACHINE.

1,140,602.

Specification of Letters Patent. Patented May 25, 1915.

Application filed May 7, 1910. Serial No. 560,013.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Cement-Applying Machines, of which the following is a specification.

My invention relates to cement applying machines, and is applicable for applying opposed strips of cement, preferably to the edges of articles, such as vamps or other parts of foot wear, or other articles, in the manufacture of the same.

15 The parts to be cemented are often in duplicate, or are rights and lefts, or are so shaped that they may be folded or placed face to face, when the edges of the same will be coincident and of the same contour. 20 When so arranged the finished sides of the pieces will face each other, and the unfinished sides, to which the cement is applied, will be outside faces.

It is the object of my invention to provide 25 novel means whereby the strips of cement may be applied to both of the unfinished surfaces which are on the outside of the mated or pair of parts, applying both strips of cement at the same time, thus providing 30 economy of manufacture.

My invention consists in providing a cement applying machine having opposed cement-applying means acting simultaneously upon the stock; further in providing opposed feeding means and opposed cement-applying means acting side by side upon the stock; further in providing rotary cement-applying brushes which are arranged 35 to extend into each other's circles of rotation when in idle relation and arranged to receive the stock between them; further in providing rotary cement-applicers located opposite each other and feeding means at the side of said rotary cement-applicers so 40 arranged that the feeding means locate the position of the stock at the side of the rotary cement-applicers and the rotary cement-applicers act upon each other as cushions; and, further, in providing novel means in a cement applying machine whereby the stock 45 is stripped from the cement-applying means.

The invention will be further readily understood from the following description and claims, and from the drawings, in which 50 latter:

Figure 1 is a front elevation of my improved device, partly broken away. Fig. 2 is a rear elevation of the same, partly broken away. Fig. 3 is an end elevation of the same, partly broken away. Fig. 4 is a vertical section of my improved device, partly broken away, taken in the axial planes of the feed-shafts, on the line $z-z$ of Fig. 3. Fig. 5 is a cross-section of the same on the line $y-y$ of Fig. 1. Fig. 6 is a cross-section of the same on the line $x-x$ of Fig. 1. Fig. 7 is an end elevation, with parts partly broken away for better illustration, showing the action of the opposed brushes upon the stock. Fig. 8 is an axial section of the same taken on a line corresponding to the line $w-w$ of Fig. 7. Fig. 9 is a front elevation of my improved device, partly broken away, showing the supplemental frame in retracted position. Fig. 10 is a cross-section of the same on the line $v-v$ of Fig. 9; and, Fig. 11 is a side elevation of the barrel of the rotary brush.

1 represents the frame which in the form shown comprises a column 2, having a goose-neck extension 3 provided with a hanger 4.

5 is an operating shaft. This shaft may be driven by a pulley 6 or other suitable means. It is also arranged to act as a feed-shaft in manner hereinafter explained. The 85 operating shaft has a bearing 7 in the column and a bearing 8 in the hanger. It has a gear 9 secured thereto which meshes with a gear 10 on a shaft 11 journaled in a bearing 12 in the hanger, the latter shaft also 90 having thereon a gear 13 which meshes with a gear 14 on a sleeve 15 rotatable about the operating shaft.

A feed-wheel 16 is secured to the operating shaft so as to rotate therewith, as in the 95 direction of the arrow a , and a rotary cement-applicer 17 is secured to the sleeve so as to rotate with the sleeve, preferably in the same direction as the direction of rotation of the feed wheel. The train of gearing 9 10 13 100 14 is preferably so proportioned and arranged as to rotate the rotary cement-applicer 17 with greater peripheral speed than the peripheral speed of the feed-wheel 16, for purposes hereinafter explained.

18 is a rotary cement-supplying roller secured to a shaft 19 journaled in bearings 20 21 on a cement-supplying head 22. The roller preferably rotates in the direction of the arrow b . The shaft 19 has a gear 23 110

thereon which meshes with the gear 13. The head 22 is rigid with the frame, as by being screwed to the threaded end of a shank having a cement-conduit 25 therein, for clamping the parts upon a bearing 24 on the frame. The cement-conduit 25 is continued in the head and communicates with a cement-pot 26 in which a supply of cement is contained, the lower end of the pot having a removable cement-sieve 27 therein, which is spaced from the bottom of the pot, the pot being arranged to be closed by a cover 28 suitably secured in place. There is a cement-valve 29 in the cement-conduit in the head for regulating or shutting off the supply of cement from the pot 26.

31 is a movable frame shown as a swinging housing pivoted on trunnion-screws 32 to the main frame. This movable frame comprises a bearing 33 having a feed-shaft 34 journaled therein. This feed-shaft has thereon a gear 35 which is meshed by a gear 36 secured to the operating shaft. In its preferred form the pivotal axes of the trunnion-screws 32 are in vertical plane with the outer ends of the meshing teeth of the gears 35 36 and in horizontal plane with the pitch lines of said teeth at their meeting points, (see Figs. 1, 9 and 10), so that, when the swinging frame is moved on its pivots the gears are maintained in full mesh with each other at their outer ends, while the relative movement between the gears at their inner ends is a receding movement for preventing binding of any parts, the construction being such as to cause only slight variation in meshing relation between said gears during movement of said movable frame, the slight variation taking place being a relieving variation. The movable frame may have a clip 37 secured thereto for limiting movement of the gear 35 and feed-shaft 34 toward the gear 36 and the feed shaft 5.

There is a gear 30 on the feed-shaft 34 which meshes with a gear 38 secured to a shaft 39 journaled in a bearing 40 on the movable frame, the said shaft having a further gear 41 thereon which meshes with a gear 42 on a sleeve 43 journaled about the feed-shaft 34, the said sleeve having a rotary cement-applier 44 suitably removably secured thereto, as by a set-screw 45. The said shaft has a feed-wheel 46 secured thereto, which preferably rotates in the direction of the arrow *c*, the rotary cement-applier 44 rotating in similar direction.

The train of gearing 30 38 41 42 is preferably so arranged as to cause the rotary cement-applier 44 to rotate with a peripheral speed greater than the peripheral speed of said feed-wheel 46. The parts are preferably so arranged that the rotary cement-appliers 17 44 and the feed-wheels 16 46 will rotate in opposite directions as indicated by the arrows, and be opposed to each other

for the purpose of simultaneously acting opposingly on the opposite sides of the stock, shown at 47, fed between the same, preferably in the direction of the arrow *d*, constituting the machine of a duplex-applying machine, the term duplex indicating that the cement application takes place upon both of the exposed sides of the stock during the same operation.

51 is a cement-supplying roller secured to a shaft 52 journaled in bearings 53 54 of a cement-supplying head 55 on the movable frame. (See Figs. 1, 2 and 4.) The shaft 52 has a gear 56 thereon which meshes with the gear 41, causing the cement-roller 51 to rotate in the direction of the arrow *e*. (See Fig. 3.) A cement-conduit 57 communicates with the cement-supplying head 55, a suitable valve 58 regulating or shutting off the supply of cement to said head:

There is a cement-pot 59 communicating with the conduit, which may be provided with a removable cement-sieve 60 and be provided with a cover 61 suitably secured thereto.

The upper portion of the cement-conduit 57 and the cement-pot 59 may be a separable portion of the movable frame, held in place by the screws 62 and provided with an opening 63 to accommodate the rear trunnion-screw 32, upon which the movable frame is pivoted and the cement-supplying head and lower portion of the cement-conduit may be a separable part of the movable frame held in place by screws 64, (see Figs. 1 and 9) the upper and lower portions of the cement-conduit being adjustably connected by the right and left hand nipple 65. The movable frame is substantially balanced by mounting the cement-pot partially at one side of the vertical plane of the pivotal axes of the movable frame while the cement-applier 44 and the head 55 therefor are mounted at the other side of said vertical plane, and by the provision of a spring 66 between the main and movable frames.

The movable frame with the rotary cement-applier 44, the feed-wheel 46, cement-supplying roller 51, cement-supplying head 55, cement-conduit 57 and cement-pot 59, oscillate together upon the pivotal axes of the movable frame for causing reciprocation between the rotary cement-appliers 17 44 and the feed-wheels 16 46, there being yielding movement between these latter parts when the stock is fed between them. This yielding movement is assisted preferably by a spring 67 between the main and movable frames, shown as received in the bore of a hollow screw 68 threaded in a lug 69 of the movable frame, the other end of the spring being received in a positioning-recess 70 of the main frame.

The extent of approach between the frames is regulated by a set-screw 71 shown as on

the movable frame, held in adjusted positions by a jam-nut 72, and arranged to strike the end of a screw 73 on the main frame. (See Figs. 2 and 3).

5 I prefer to locate the rotary cement-applifiers respectively adjacent to the feed-wheels 16 46, the said respective rotary cement-applifiers and feed-wheels having common rotary axes. I prefer further to provide 10 take-offs for the stock between the rotary cement-applifiers and the feed-wheels which serve the purpose of releasing the stock from the rotary cement-applifiers, it being understood that the cement applied by my improved device is usually a viscous substance. 15 76 77 represent the stock take-offs and are shown as plates respectively received loosely between the rotary cement-applier 17 and feed-wheel 16 and between the rotary cement-applier 44 and feed-wheel 46.

20 The outer edges of these take-offs, at the stock-contacting portions of the feed-wheels, are within the longitudinal projections of the peripheries of said feed-wheels respectively. At the feed-out sides of the said feed-wheels however, that is, the sides thereof at which the stock leaves the feed-wheels, these take-offs are provided with outwardly projecting portions 78 79 which project out 25 side the longitudinal projections of the respective feed-wheels, and are shown as eccentric portions, eccentric to the circles of the respective feed-wheels and rotary cement-applifiers. These take-offs preferably 30 terminate in tails 80 81 received across the cement-supplying rollers 18 51 respectively for preventing contact of the stock with said cement supplying rollers. These tails also 35 serve as handles for manually swinging the 40 take-offs.

The stock as it leaves either rotary cement-applier has a tendency to adhere thereto, but contacting the take-off edge of the take-off, it is held away from the rotary cement-applier, the stock being thereby prevented 45 from following the rotary cement-applier in its movement, the danger of having the stock carried around the rotary cement-applier or into contact with the cement-supplying 50 roller being thereby avoided.

The construction and arrangement of the stock take-off also permits the stock take-off to be located closely adjacent to and between the rotary cement-applier and the feed-wheel, thereby having the further advantage 55 of separating the rotary cement-applier from the feed-wheel for aiding in avoiding application of cement to the feed-wheel and separating the rotary cement-applier and 60 feed-wheel by a normally stationary plate for preventing relative influence between the rotary cement-applier and feed-wheel tending to disarrange the parts by reason of their relatively different speeds.

In the form shown the take-off plates are

respectively provided with bearing flanges 82 83 about the respective feed-wheel shafts 5 34 between the respective shoulders 84 85 on said shafts, against which the feed-wheels are respectively received, and the outer ends 70 of the sleeves which support the rotary cement-applifiers. The rotations of the feed-wheels and cement-applifiers normally cause the tails of the take-off plates to respectively contact the cement-supplying heads. 75

The stock-contacting points of the peripheries of the respective feed-wheels are normally closely adjacent to each other, as shown in Fig. 3, and the rotary cement-applifiers are of greater diameter than the diameters of the respective feed-wheels. The peripheries of the rotary cement-applifiers preferably intersect each other when in idle relation, as indicated in Figs. 3, 4 and 5. The ends of the bristles of the respective opposed rotary cement-applying brushes extend past each other at the points of closest approach between said rotary brushes.

When now, stock is fed between the feed-wheels, these are separated by the stock, the feed-wheels, however, exerting continuing feeding pressure on the stock, but they definitely locate the stock between the rotary cement-applifiers by contact with the stock adjacent its edge. These latter, being of greater diameter than the feed-wheels, press with yielding pressure upon the respective exposed sides of the stock, thereby acting as cushions for each other with the effect of permitting the rotary cement-applifiers to 90 work or force the cement into the pores or between the fibers of the stock, the edges of the stock yielding more or less toward one side or the other, depending on the relative 95 conditions of the rotary cement-applifiers. 100

The feed-wheels act with greater pressure upon the stock than the bristles of the rotary brushes, for providing definite feeding relation of slower speed than the peripheral speed of the rotary brushes, the rotary 110 brushes acting oppositely upon the outer faces of the stock with a wiping action as more clearly shown in Figs. 7 and 8.

It is desirable that there shall be a free flow of cement during operation of the 115 machine, but that the flow shall cease when operation ceases so as not to waste the cement or permit the cement-supplying heads to leak, and also that surplus cement shall be directed back into the cement-supplying heads. For accomplishing these ends, I provide the periphery of each of the cement-supplying rollers with cement-supplying recesses 86 which form pockets (see Figs. 5, 7 and 8) into which the bristles 120 of the brushes are flexed for wiping the cement therefrom and carrying the cement to the stock with a brushing action, the peripheries of the brushes moving faster 125 than the stock. 130

The formation of the recesses forms ribs 87 in the periphery of the cement-supplying roller, which separate the pockets. For forming a continuous cement-supply to the brushes, grooves 88 are provided crosswise of these ribs which connect with the adjacent pockets. The pockets preferably gradually decrease in cross-sectional area toward their lateral ends, and the grooves also preferably decrease in cross-sectional area toward the lateral ends of the ribs, as indicated in Fig. 8.

The purpose of this construction is to provide the greatest supply of cement adjacent to the middle of the width of cement application, this supply decreasing toward the edges of cement application. The brushes in applying the cement will tend to spread the cement under this arrangement throughout the width of cement application substantially even, while at the same time excess of cement at the edges of cement application and waste of material will be avoided.

The respective cement-supplying heads 25 have cement-supplying reservoirs 91 92 therein. The heads, at the reservoirs, are of similar construction, the reservoir of the upper head however being above the cement-supplying roller and the reservoir for the lower head being below the cement-supplying roller. I shall describe the upper reservoir and adjacent parts, the lower reservoir and adjacent parts being of similar construction and reference thereto being made by similar reference numerals preceded by the numeral 1. Thus the head 22 has cheeks 93 94 which contact the periphery of the cement-supplying roller 18 at the ends of the recesses 86 therein. 95 is a cement-wiping lip on the head which extends across the recesses 86 and is closely adjacent to the periphery of the roller for causing the proper filling of the recesses 86 and grooves 88, the cheeks preventing spreading of the cement 45 in said head on the periphery of the roller laterally beyond said recesses and grooves, for supplying the cement within proper range to the rotary cement-applier. The head is also provided with a cement-receiving mouth 96 opposite said lip, into which the surplus cement on the roller is received for returning the same to the reservoir.

101 102 are guards secured to the respective heads and respectively have fingers 103 55 104 received about the feed-in edges of the feed-wheels for aiding in directing the stock between the feed-wheels and protecting the operator from contact with the feed-wheels.

60 105 is a cement-wiping finger for the feed-wheel 16. It extends across the outer face of the feed-wheel toward the cement-supplying roller 18, preferably contacting the periphery of said roller, and wipes the outer face of said roller for keeping the feeding-

in portion of said roller clean and directing the cement there may be thereon into contact with the cement-supplying roller which feeds it back into the reservoir. This cement-wiping finger is preferably located 70 to rear of a right line drawn between the rotary axes of the feed-wheel 16 and cement-supplying roller 18. (See Figs. 1, 3, 5 and 9.) The finger has a shank 106 which is adjustably received in an aperture 75 in a lug 107 on the guard 101 and held in place by a thumb-screw 108. The guard also has thereon a cement-wiping finger 109 arranged to contact the flange 110 of the rotary cement-applier 17 for directing any 80 cement there may be on the outer face of said flange toward the bristles of the brush.

111 is a cement-wiping finger for the feed-wheel 46, the end of the finger being presented to the cement-supplying roller 51. 85 (See Figs. 1, 3, 5 and 9.) This finger wipes the outer face of the feed-wheel 46 of any cement there may be thereon toward the roller 51, which conveys the wiped cement back into the reservoir 92. The said finger 90 is preferably located to rear of a right line drawn between the rotary axes of the feed-wheel 46 and the cement-supplying roller 51. It has a shank 112 adjustably received in an aperture in a lug 113 on the guard 102 and 95 held in place by a thumb-screw 114. The guard 102 also has a cement-wiping finger 115 for the rotary cement-applier 44. It 100 wipes the face of the flange 116 of the lower rotary brush and directs any cement there may be thereon toward the bristles thereof.

Cleanliness of cement application is provided by these means. Ready access to the reservoir 91 is provided by a threaded plug 117 and ready access to the reservoir 92 is 105 provided by a threaded plug 118, the threaded plugs screwing into the walls of the respective reservoirs.

121 is a stock-gage which is small in cross-section and is arranged to be received between the peripheral edges of the flanges 110 and may be placed closely adjacent to the bristles of the brushes adjacent the points of nearest approach between the latter for enabling the strip of cement to be 110 applied close to the edge of the stock and enabling the stock to be readily shifted for guiding edges of markedly irregular shapes across the said gage. The gage is adjustable toward and from the rotary cement-appliers, as by being provided with a slot 122 through which a screw 123 is received into a lug 124 on the frame.

For enabling the cement-appliers to be separated when not in use, I provide a lever 125 125 having a bearing 126 about the operating shaft and a separating lug 127 arranged to bear against the movable frame for forcing the cement-applier thereon away from the cement-applier on the main frame. (See 130 135

Figs. 9 and 10.) The separating lever may be thrown back out of the way by swinging the same about its pivotal connection with the operating shaft 5 through the opening below the goose-neck 8 for resting upon a lug 128 on the cement-conduit for the movable frame.

- I prefer to construct the cement-applying brushes respectively by providing a bristles-
10 supporting barrel 131 having a bearing 132 which fits the driving-sleeve therefor. The barrel has a bore 133 of greater diameter than the bore of the bearing 132. The bristles are gathered in tufts and secured in
15 apertures 134 preferably by means of wires 135 which are received into said apertures from the wall of the bore 133, the greater diameter of the bore 133 accommodating the stretches of wire between the apertures.
20 These apertures are arranged in rows around the barrel 131 and preferably extend radially thereof. The apertures of adjacent rows are preferably arranged in advance of each other, so that the apertures of adjacent rows will not register side-by side. At one end of the barrel, the flange (see the flanges 110) is located, adjacent to which there is a row of bristle-tufts. Next to this row of bristle-tufts a
25 plate-collar 136 is received about the barrel 131, then follow other alternate rows of bristle-tufts and plate-collars, the spaces between the collars forming annular channels in which the respective rows of the bristles are located, the plates preventing undue lateral flexing of the bristles and causing the bristles to bend in channels which extend around the barrel, thereby holding the bristles of the rotary brush up to their work
30 and aiding in stiffening the same so that the bristles may be caused to firmly rub the cement between the fibers or into the pores of the stock being cemented.
35 The separation of the annular rows of bristles by the washers and the arrangement of the tufts of bristles in unmating relation side by side also permits the brush to receive and deliver a maximum amount of cement, the construction further holding
40 the respective bristle-tufts within the prescribed limits.
45 Having thus fully described my invention, what I claim as new and desire to secure by Letters Patent is:
50 1. In a duplex cement applying machine for flexible material, the combination of opposed feeding means having opposed feeding-faces for the material arranged to contact said material in a line slightly removed from the edge of the material, whereby a narrow margin of said material overhangs
55 said feeding means, and opposed cement-applying means provided with cement-applying faces closely adjacent to said opposed feeding-faces, said cement-applying faces
60 being resilient throughout their areas and solely supporting said overhanging margin at both sides of the latter whereby to flex said overhanging margin from the point of contact with the material by said opposed feeding-faces selectively throughout the width of said margin into the normal planes of opposite ones of said cement-applying faces.

2. In a duplex cement applying machine for flexible material, the combination of opposed feeding means having opposed feeding-faces for the material arranged to contact said material in a line slightly removed from the edge of said material whereby a narrow margin of said material overhangs said feeding means, and opposed rotary cement-applying brushes, said rotary cement-applying brushes solely supporting both sides of said overhanging margin whereby to flex said overhanging margin selectively toward both said brushes, said feeding faces defining the limit of extent of flexing of said margin at one side thereof, said rotary brushes acting as cushioning means throughout their widths for selective flexure toward either brush of the various portions in width of said margin.

3. In a duplex cement applying machine for flexible material, the combination of opposed feeding means having opposed feeding-faces for the material arranged to contact said material in a line slightly removed from the edge of the material, whereby a narrow margin of said material overhangs said feeding means, and opposed cement-applying means provided with cement-applying faces closely adjacent to said opposed feeding-faces, said cement-applying faces being resilient throughout their areas and solely supporting said overhanging margin at both sides of the latter whereby to flex said overhanging margin at various points throughout its width into the normal planes of opposite ones of said cement-applying faces, a gage for the edge of the material, the said flexure of the margin of the material located between said opposed feeding-faces and said gage.

4. In a duplex cement applying machine for flexible material, the combination of opposed feeding means having opposed feeding-faces for the material arranged to contact said material in a line slightly removed from the edge of said material whereby a narrow margin of said material overhangs said feeding means, and opposed rotary cement-applying brushes, said rotary cement-applying brushes solely supporting both sides of said overhanging margin whereby to flex said overhanging margin selectively toward both said brushes, said feeding faces defining the limit of extent of flexing of said margin at one side thereof, said rotary brushes acting as cushioning means through-

- out their widths for selective flexure toward either brush of the various portions in width of said margin, a gage for the edge of the material, the said flexure of the margin of the material located between said opposed feeding-faces and said gage.
5. In a cement applying machine, the combination of a rotary cement-applying brush arranged to apply cement to the margin of material and provided with a flange and bristles extending beyond the periphery of said flange, cement - feeding means for said brush, and a cement-wiping finger acting on said flange for directing the cement 10 on said flange toward said bristles after the contact of said bristles with said cement-feeding means and prior to the contact of said bristles with said material.
15. In a duplex cement applying machine, the combination of a main frame, a drive-shaft therein, a rotary cement - applying brush and feed-wheel therefor, a movable supplemental frame, a rotary cement-applying brush and feed-wheel therefor, driving means between said frame, and a separating lever acting on said frames for separating said rotary cement - applying brushes and feed-wheels on said respective frames, substantially as described.
20. In a cement applying machine, the combination of a rotary cement applicer and feed-wheel located end to end, and a stock take-off located between said rotary cement applicer and feed-wheel and projecting outwardly beyond the longitudinal projections of the peripheries of said rotary cement applicer and feed-wheel.
25. In a cement applying machine, the combination of a rotary cement applicer and feed-wheel located end to end, a stock take-off located between said rotary cement applicer and feed-wheel and having a projecting portion projecting outside the longitudinal projections of the peripheries of said rotary cement applicer and feed-wheel, and having a limiting extension arranged to contact a machine-part for positioning said take-off, substantially as described.
30. In a cement applying machine, the combination of a rotary cement applicer and a feed-wheel located end to end, a stock take-off located between said rotary cement applicer and feed-wheel and having a portion projecting outwardly beyond the longitudinal projections of the peripheries of said rotary cement applicer and feed-wheel, and means for limiting turning of said plate for providing a stationary plate between said rotary cement applicer and feed-wheel during operation, substantially as described.
35. In a cement applying machine, the combination of a rotary cement applicer and feed-wheel arranged end to end, a stock take-off in the form of a plate between said rotary cement applicer and feed-wheel, and a cement-supplying roller for said rotary cement applicer, said stock take-off having a portion which projects outwardly beyond the longitudinal projections of the peripheries of said rotary cement applicer and feed-wheel and about the exposed portion of said roller.
40. In a cement applying machine, the combination of a rotary cement applicer and feed-wheel arranged end to end, a stock take-off in the form of a plate between said rotary cement applicer and feed-wheel, a cement-supplying roller for said rotary cement applicer, and a cement-supplying head in which said roller rotates, said roller having an exposed portion outside said head between said head and rotary cement applicer, and the said stock take-off having a portion which projects outwardly beyond the longitudinal projections of the peripheries of said rotary cement applicer and feed-wheel toward said head across said exposed portion of said roller.
45. In a cement applying machine, the combination of a feed-shaft, a sleeve journaled thereon, a rotary cement-applying brush secured to said sleeve, a feed-wheel secured to said shaft, means for rotating said shaft and sleeve at different speeds, said rotary cement-applying brush having a bore of greater diameter than said shaft, a stock take-off in the form of a plate between said rotary cement-applying brush and feed-wheel and provided with a laterally extending annular flange received about said shaft in said bore, said stock take-off having a portion which projects outwardly beyond the longitudinal projections of the peripheries of said rotary cement applying brush and feed-wheel and arranged for directing the stock away from said brush and feed-wheel after cement application thereto, substantially as described.
50. In a cement applying machine, the combination of a rotary cement-applying brush provided with a flange and bristles extending beyond the periphery of said flange, cement - feeding means for said brush, feeding means for feeding stock past said brush, and a cement-wiping finger acting on the feed-in portion of said flange for directing the cement on said flange toward said bristles after the contact of said bristles with said cement-feeding means and prior to the contact of said bristles with said stock, substantially as described.
55. In a cement applying machine, the combination of a rotary cement-applying brush comprising bristles and a flange at one side thereof, a feed-wheel at the other

side of said bristles, said rotary cement-applying brush and feed-wheel being located end to end, a cement-supplying means for said bristles, a cement-wiping finger acting 5 on the side of said flange at the feed-in portion thereof for directing the cement thereon toward said bristles after action thereon by said cement-supplying means and prior to action thereof on said stock, 10 and a cement-wiping finger acting on the feed-out portion of the outer face of said feed-wheel, substantially as described.

15. In a cement applying machine, the combination of a rotary cement-applying brush provided with bristles and a flange at one side of said bristles, a feed-wheel at the other side of said bristles, said rotary cement-applying brush and feed-wheel arranged end to end, cement-feeding means 20 for said brush, a cement-wiping finger acting on said flange for directing the cement thereon toward the bristles of said brush, a cement-wiping finger acting on the outer face of said feed-wheel for directing the 25 cement thereon toward said cement-feeding means, said respective cement-wiping fingers being located at opposite sides of the vertical plane of the rotary axis of said brush parallel to said axis, substantially as 30 described.

16. In a cement applying machine, the combination of a rotary cement applying brush provided with bristles and a flange at one side of said bristles, a feed-wheel at the 35 other side of said bristles, said rotary cement-applying brush and feed-wheel arranged end to end, cement-feeding means for said brush, a cement-wiping finger acting on said flange for directing the cement 40 thereon toward the bristles of said brush, a cement-wiping finger acting on the outer face of said feed-wheel for directing the cement thereon toward said cement-feeding means, said respective cement-wiping 45 fingers being located at opposite sides of the vertical plane of the rotary axis of said brush parallel to said axis, and means for adjusting the lateral distance between said fingers, substantially as described.

50. 17. In a cement applying machine, the combination of a rotary cement-applying brush and a cement-supplying roller therefor, said cement-supplying roller provided with peripheral recesses forming cement-55 receiving pockets which gradually decrease in depth toward their lateral ends, the periphery of said roller having ribs between said recesses, said ribs provided with grooves connecting said recesses, and said 60 grooves decreasing in width toward the lateral ends of said ribs, substantially as described.

18. In a cement applying machine, the combination of a rotary cement-applying

brush, a cement-supplying head, a cement-supplying roller journaled therein, said head having a lip crosswise of the periphery of said cement-supplying roller, the periphery of said cement-supplying roller being provided with alternate recesses and ribs, 65 said ribs provided with grooves arranged side by side for connecting adjacent recesses, and the said recesses and grooves decreasing in cross sectional dimensions toward the lateral ends of said ribs. 70

19. In a cement applying machine, the combination of a rotary cement-applying brush, a cement-supplying roller therefor, and a cement-supplying head in which said roller is journaled, the peripheries of said 80 roller being provided with alternate recesses and ribs, the said ribs having grooves therein arranged side by side connecting adjacent recesses, the said recesses and grooves decreasing in cross-sectional dimensions toward the lateral ends of said ribs, and said head provided with cheeks for the periphery of said roller beyond the ends of said recesses and with a lip received across the 85 said recesses, substantially as described. 90

20. In a cement applying machine, the combination of rotary cement applicers and feeding means arranged in pairs, the cement-applier and feeding means of each pair arranged end to end, and a stock take-off 95 for each pair between the rotary cement applicers and feed-wheel thereof and respectively having projecting portions which project outwardly beyond the longitudinal 100 projections of the peripheries of said respective pairs, said projecting portions receding from each other, substantially as described.

21. In a duplex cement applying machine, the combination of a rotary upper 105 cement-applying brush and feed-wheel, located end to end, an upper cement-supplying roller for said rotary cement-supplying brush, a lower rotary cement-applying brush and a lower feed-wheel located end to end, a lower cement-supplying roller for said lower rotary cement-applying brush, an upper stock take-off in the form of a 110 plate between said upper rotary cement-applying roller and feed-wheel, and a lower stock take-off in the form of a plate between said lower rotary cement-applying brush and feed-wheel, said respective stock take-offs having outwardly projecting portions 115 projecting away from each other about said respective cement-supplying rollers, substantially as described. 120

22. In a cement applying machine, the combination of a rotary cement-applying brush comprising annular rows of bristles 125 and separating washers between said annular rows of bristles for providing annular grooves in which said bristles are flexed,

and a cement-supplying roller whose periphery is provided with alternate recesses and ribs and grooves arranged side by side in said ribs, the said recesses and grooves decreasing in cross-sectional dimensions toward the lateral ends of said ribs, substantially as described.

In testimony whereof, I have signed my name hereto in the presence of two subscribing witnesses.

WILLIAM F. LAUTENSCHLAGER.

Witnesses:

CONSTANT SOUTHWORTH,
LILLIAN BURNETT.

It is hereby certified that in Letters Patent No. 1,140,602, granted May 25, 1915, upon the application of William F. Lautenschlager, of Cincinnati, Ohio, for an improvement in "Cement-Applying Machines," an error appears in the printed specification requiring correction as follows: Page 2, line 122, for the word "assisted" read *resisted*; and that the said Letters Patent should be read with this correction therein that the same may conform to the record of the case in the Patent Office.

Signed and sealed this 15th day of June, A. D., 1915.

[SEAL.]

J. T. NEWTON,

Acting Commissioner of Patents.
